(57) **CLAIM**

The ornamental design for a two piece body clip set (right and left) for a toy car having a removable body, as shown and described.

DESCRIPTION

FIG. 1 is an isometric front view of the left side body clip of the set that can be inserted into a slot in a left hand side of a toy car chassis (such as an HO scale slot car offered by AFX™, Tomy™, or BSRT™);

FIG. 2 is an isometric rear view of the right side body clip of the set that can be inserted into a slot in a right hand side of a removable toy car body (such as an HO scale slot car body from AFX™, Tomy™, Johnny Lightning™, or Auto World™);

FIG. 3 is another isometric rear view of the right side body clip of the set;

FIG. 4 is an isometric rear view of the left side body clip of the set;

FIG. 5 is an isometric front view of the right side body clip of the set; and,

FIG. 6 is another isometric front view of the left side body clip of the set.

The toy car chassis and toy car body shown in broken lines in FIGS. 1 and 2 represent exemplary environment elements in which the article resides and forms no part of the claimed design.
